UNITED STATES PATENT OFFICE.

LEON KNASTER, OF WEST HOBOKEN, NEW JERSEY.

SECRET CABINET.

Application filed December 14, 1923. Serial No. 680,725.

To all whom it may concern:

Be it known that I, LEON KNASTER, a citizen of the United States, residing at West Hoboken, in the county of Hudson and State of New Jersey, have invented certain new and useful Improvements in Secret Cabinets, of which the following is a specification.

This invention has to do with improvements in that type of furniture disclosed in my co-pending application for improvements in secret cabinets, Serial Number 635,370, filed April 28, 1923.

As in the before-mentioned application, the primary idea involved herein is the provision of a normally appearing article of furniture, especially useful in homes and elsewhere, but which in reality embodies in its construction secret compartments or safe deposit receptacles inaccessible to any unacquainted with the necessary manipulations of the parts to disclose them. In so far as the general features of construction are concerned, the present improvements closely follow those shown in my previous application, and the object in view has been to eliminate some of the disadvantages inhering in the details of the arrangement, as will be made more clear hereinafter.

More specifically speaking, the secret compartments in my former invention are located in the rear portion of the desk or article of furniture and access to these is had by the dropping down of the back walls or sections thereof. This makes it necessary to pull the piece of furniture entirely away from the side of the room against which it is usually disposed, thus unnecessarily marring the floor and entailing movement of a heavy object by persons physically unable, perhaps, to perform the labor without help. My present invention is designed to either partially or entirely do away with this, depending upon the parts to which access is desired, incidentally eliminating at the same time the probability of accidental discovery of the secret character of the construction.

A further improvement over my previous construction is involved in the arrangement of one of the secret compartments upon the back of the desk and the mounting of said back so that it will readily move vertically from its normal position into an elevated one, rendering the second of the secret compartments accessible, the first com-

partment mentioned being locked against any displacement through the coaction of the top of the desk intercepting the path of its vertical travel.

Other refinements and improvements in the former construction will be hereinafter specifically referred to and disclosed in the drawings, wherein:

Figure 1 is a rear elevation of a desk 65 constructed in accordance with this invention, showing the back section and secret compartment in elevated position disclosing the inner safe compartment;

Figure 2 is a fragmentary top plan view 70 showing the sliding top drawn back to render the back secret compartment accessible and release it for movement;

Figure 3 is a longitudinal sectional view 75 disclosing the details of construction, the back secret compartment being raised and locked in elevated position;

Figure 4 is a vertical section taken about on the plane indicated by the line 4—4 of Figure 3, looking in the direction of the 80 arrows;

Figure 5 is a horizontal sectional view on the line 5—5 of Figure 3, looking upwardly in the direction of the arrows; and

Figure 6 is a fragmentary detail view 85 showing the secret catch device coacting with the cover operating drawer.

Like numerals refer to like parts throughout the several figures of the drawing.

Specifically describing the construction of my invention, A designates the body portion of a desk mounted upon the legs B, the particular form or style of construction being a matter of choice or design. The cabinet section C includes the pigeon holes 1, in advance of which is the table section 2 with a folding leaf extension 3 which is designed when closed to lie below the plane of the sides of the desk body, as shown in dotted lines in Figure 3, and when swung about its hinged connections 4, will meet and rest upon the drawer 5 when the latter is pulled into outermost position, the drawer thus constituting a support for the extension leaf tending to prevent breakage of the hinge 105 connection from pressure upon its surface when in use. This drawer is provided with a lock 6 operated by any suitable key and is designed, as in my previous case, to have a normal restricted opening movement controlled by the concealed or secret pivoted stop 8 which is designed to coact with the

rear wall 5^a of the drawer for limiting the initial outward movement. This stop is held depressed into the path of movement of the rear wall of the drawer by the spring 10 and is capable of displacement by an actuating lever 11 pivoted at 12 beneath the partition 13, the location of which lever is of course supposed to be a matter of knowledge to the owner of the desk only.

10 The free end 11^a of the lever 11 lies in such position, in other words, that it will not be seen but it may be operated by reaching in when the drawer is open. Shifting it laterally will raise the catch and enable 15 the drawer 5 to be pulled to its outermost position, shown in full lines in Figure 3. The purpose of this will now be set forth.

Slidably mounted in the sides of the desk is a curved cover 14 which is adapted to 20 close the pigeon hole compartment 1, this compartment for purposes of distinction being termed a public compartment. The cover when in closed position rests upon the free extremity of the folding leaf extension 3 so that this will be locked in such position when the desk is not in use. This forms an important feature of my construction but will not be more specifically referred to in view of the fact that it is the 25 subject-matter of my co-pending application for improvements in furniture construction, filed of even date herewith.

The cover 14 is connected by means of the link 16 to the bracket 17^a attached to the 30 rear wall 5^a of the drawer 5, so that when the drawer is moved outwardly it will be automatically lifted or opened and correspondingly the inward movement of the drawer will close the cover.

40 As in the case of my previous invention, the cover 14 has two degrees of movement, that depicted by the dotted lines being the normal and that by the full lines the abnormal position. For ordinary purposes the 45 opening of the cover to its first limit of movement is sufficient, but when the drawer is released from the catch 8 in the manner hereinbefore described, the cover may be moved by said drawer into the abnormal position, thereby rendering accessible a 50 further secret locking member in the form of a pivoted catch lever 17 mounted in a countersink beneath the desk top 18. The lever is pivoted at 19 and is formed with a hooked extremity to engage with the catch 20 attached to the inner face of the back 21 of the desk. A spring 19^a is preferably provided to normally hold the lever 17 in engaging relation so that it will automatically 55 engage with the catch 20 when the top 18 is shifted. The top 18, it will be apparent, is mounted to slide forwardly into the full line position shown in Figure 3 when the lever 17 has been disengaged, which may be 60 easily accomplished by inserting the fingers

beneath the top 18 when the cover 14 has been shifted back the full limit of its movement.

The purpose of this movement of the top is to afford access to the secret compartments of the desk, and of course the operation of the parts as before described will be known only to those who have authorized access. I preferably provide two secret receptacles, one designated 24 and the other 75 or innermost main compartment 25.

The important difference between this invention and my previous one resides in the construction and arrangement of the first of these compartments. Whereas, formerly 80 I employed a pivoted or outwardly swinging back, in my present construction I prefer to mount the back 21 to slide vertically, and instead of having a separate file box or receptacle, I form the compartment 24 85 by attaching a properly shaped metal wall to the back 21 so that this compartment will necessarily move with the back when the latter is raised to admit of access to the main compartment 25. I have thus done 90 away with several disadvantages, for with a pivoted back as before mention, it is necessary to move the desk completely away from the wall to permit it to open and the possibility of accidental discovery of the 95 secret compartment was greater, due to the tendency of the back to drop down upon the disengagement of the lock holding it up. Further, to obtain access to the main compartment it was necessary both to drop the 100 back down and remove the auxiliary or file receptacle.

The front wall of the compartment 24 is provided with a hand hole 22 as seen best in Figure 4, by means of which the 105 compartment is elevated readily, and spring-actuated catches 23 mounted in slots in the edges of the back 21 automatically project to engage with the top of the sides of the desk when the compartment is raised 110 to its uppermost position shown in Figure 4. When it is desired to lower the compartment the catches 23 are pressed inwardly and the frictional contact of these catches is sufficient to brake the falling 115 movement in order to prevent sudden drop of the back.

Obviously when the compartment 24 is in its lowermost position and the top 18 is slid thereover, the back is locked against displacement. When the top is moved forwardly, access to the compartment 24, which is open at the top, is easily had without any movement of the said compartment itself. The lesser important papers or 125 documents may be kept in this receptacle. When it is desired to obtain access to the compartment 25, however, the back 21 is raised.

This innermost secret compartment is so 130

constructed as to be fire-proof and burglar-proof, having inner and outer metal walls 28 with interposed insulation 29. Into this is slidably received the metal drawer 30 on 5 the front of which is provided a permutation lock 34.

In order to provide for a very easy sliding movement of the top 18, metal plates 35 are secured to the upper edges of the 10 sides of the cabinet C, and securing slide plates 36 are attached to the top to interlock with the plates 35 and afford a sliding rail surface. In the same manner the sliding movement of the back or the secret 15 compartment 24 is facilitated by the provision of interlocking slide plates 37 and 38. In connection with the latter, stop extensions 39 are arranged so as to coact with stop screws 40 on the inner faces of the 20 cabinet sides to thereby limit the elevating movement of the compartment and prevent complete displacement normally.

It will be apparent from the foregoing that this arrangement and construction of 25 the rear section of my desk is a most desired improvement over that employed in my previous invention and I wish it to be understood that further changes in the details and construction may be made without departing from the spirit of the invention and within the scope of the claims hereto appended.

Having thus described my invention, what I claim as new and desire to secure 35 by Letters Patent is:

1. In a cabinet of the class described, provided with an opening at the back for access to a compartment, a shiftable top section, a back section slidably mounted for 40 vertical movement between the sides of the cabinet to close said opening, said top section being arranged to engage over the back section aforesaid to prevent displacement of the latter until the top section is shifted, and a compartment adapted to be 45 rendered accessible from said opening when the back section is shifted vertically.

2. In a cabinet of the class described, a 50 shiftable top section, a back section slidably mounted for vertical movement be-

tween the sides of the cabinet and adapted to close an opening therein, said top section being arranged to engage over the back section aforesaid to prevent displacement of the latter until the top section is shifted, 55 a secret compartment mounted upon said back section, and a secret compartment occluded by said back section and rendered accessible at said opening upon the shifting of the top and back sections. 60

3. In a secret cabinet of the class described provided with an opening at the back for access to a compartment, the combination of a front cover member, operating means for said cover member, a top section shiftable horizontally, a shiftable back section mounted to close said opening at the back and carrying a locking member, a compartment supported by said back section, and a manually operable locking member 70 mounted upon the under face of the top section to engage the locking member of the back section whereby to interlock the top and back sections. 75

4. In a secret cabinet of the class described, the combination with a front cover member, operating means therefor, said operating means constituting a drawer, means for limiting the movements of the cover member to normal and abnormal positions, 80 a shiftable top member, an auxiliary compartment beneath the top member and mounted upon the back section of the cabinet, said back section being shiftable vertically to raise the compartment and permit access to the rear of the cabinet, interlocking rail plates for said top and back sections, automatically engaging interlocking means intermediate the top and back sections for preventing movement of the 85 top section, and a main secret compartment intermediate the cover member and the drawer and normally closed against access by the auxiliary compartment and rendered accessible by raising the back section. 90 95

In testimony whereof I affix my signature.

LEON KNASTER.
